UNITED STATES PATENT OFFICE.

VIVIAN H. BURROWS, OF CHICAGO, ILLINOIS.

DESIGN FOR A VIOLIN.

45,986.

Specification for Design.

Patented June 23, 1914.

Application filed October 13, 1913. Serial No. 795,019. Term of patent 7 years.

To all whom it may concern:

Be it known that I, VIVIAN H. BURROWS, a citizen of the United States, residing at Chicago, in the county of Cook and State of Illinois, have invented a new, original, and ornamental Design for a Violin, of which the following is a specification, reference being had to the accompanying drawing, forming part thereof.

The figure is a perspective of a violin showing my design.

I claim:

The ornamental design for a violin, as shown.

VIVIAN H. BURROWS.

Witnesses:

R. J. JACKER,
MARTIN H. OLSEN.
